COMBINED LIQUID DISPENSER AND CONTAINER

Dann T. Deaver, Mount Clemens, Mich., assignor to The Delman Company, Cookeville, Tenn., a corporation of Tennessee

Filed Dec. 27, 1960, Ser. No. 63,331

Term of patent 14 years

(Cl. D58—17)

FIG. 1 is a top plan view of a combined liquid dispenser and container showing my new design;

FIG. 2 is an elevational view thereof;

FIG. 3 is an elevational view thereof, taken at right angles to the view of FIG. 2; and

FIG. 4 is a fragmentary perspective view of the top portion thereof.

The rear and side not shown are the same as the respective front and side shown.

I claim:

The ornamental design for a combined liquid dispenser and container, substantially as shown and described.
